UNITED STATES PATENT OFFICE.

JOHN PEARSON, OF CHICAGO, ILLINOIS.

CAR ROOF.

Application filed September 15, 1921. Serial No. 500,763.

To all whom it may concern:

Be it known that I, JOHN PEARSON, a citizen of the United States, residing at Chicago, in the county of Cook, State of Illinois, United States of America, having invented certain new and useful Improvements in Car Roofs, do hereby declare that the following is a full, clear, and exact description of the same.

10 My invention relates to car-roofs, and consists in the novel and useful constructions herein described and then pointed out in the appended claims.

In the accompanying drawings, which 15 illustrate practical embodiments of the various features of my invention and in which the same reference numerals indicate similar parts in the different figures, Fig. 1 is a top plan view of part of a car-roof embodying the features of my invention with various parts cut-away to afford better illustration; Fig. 2 is a cross-sectional view along the line of one of the carlines with its top-cap and end-cap omitted; Fig. 3 is a detail 25 sectional view of one of the carlines and associated parts; Fig. 4 is a detail view partly in section and partly in perspective showing one of the end-caps in place, and Fig. 5 is a detail sectional view on the line 5—5 in 30 Fig. 1.

In the drawings the reference numeral 1 indicates the ridge-pole, 2 the side-plates, 3 the side-sheathing, 4 the end or body carlines, 5 the longitudinal wooden purlines, 35 and 6 the roof-boards extending from the ridge-pole to the side-plates; the ridge-pole and body carlines are oppositely inclined from their centers to conform to the pitch of the roof. Extending transversely of the 40 roof at suitable intervals are the carlines which in the present invention are composed of wooden sub-carlines 7 and metal top-plates 8 extending from the ridge-pole to the side-plates. The bodies of the sub-carlines 7 are rabbeted at each side to form 45 seats for the sides of the metallic roof-panels 9, and they are bolted to the ridge-pole and purlines by bolts 10 having their heads countersunk into their ridges or raised central 50 portions 11. The top-plates 8 are of less width than the lower portions of the sub-carlines, but are wider than their ridges to which they are secured by wood-screws 12 having their heads countersunk therein. 55 The inner ends of the opposite sections of each carline are straddled by a suitable me-

tallic ridge-cap 13 which is bolted as at 14 to the ridge-pole. The outer end of the body of each sub-carline is shouldered or cut-away on its lower side as at 15 to allow its 60 ridge 11 to overlie a wooden strip 16 arranged upon the side-plate 2 against which the outer ends of the roof-boards 6 abut, and the outer end of each top-plate 8 is reduced in width to form a depending wing 65 17 constructed to be bent down over the facia 18. A flashing 19 is arranged upon the strips 16 and facias 18 to underlie the outer ends of the ridges 11 and roof-panels 9, and a carline end-cap 20 fits over the outer 70 end of each carline, being secured to the wing 17 by a bolt 21 and having a lag-screw 22 passing through its skirt into the side-plate. The top-plate thus forms a fastening or anchor for the end-cap. 75

The roof sheets or panels 9 extend from the ridge-pole outward to the eaves resting upon the flanges of the carlines and the flashings; each sheet or panel is substantially rectangular in shape and is provided 80 with the usual upturned side-flanges 23 that lie under the plates 8 of the carlines, with sufficient clearance between the parts to allow play to the plates along their length. The seats for the roof-panels formed by the 85 side flanges of the carlines are straight from end to end and the webs or ridges 11 are of uniform height so that the roof-panels are carried on the carlines with their flanges under the top plates upon which the carline- 90 caps are in turn supported so that all these parts are interlocked.

The carline-caps are formed of sheet metal of inverted trough-shape in cross-section, each consisting of an upper horizontal 95 top 24 of sufficient width to overlap the carline-plate 8, sides 25 of sufficient depth to form a skirt reaching to the panels, and inwardly directed flanges 26 bearing on adjacent panels; they extend from the ridge-pole 100 to the eaves, and each is provided with opposite inwardly projecting ribs 27 in its sides 25 which engage the under faces of the top plate 8 of the carline. These ribs are formed by inwardly bending or swaging the 105 material of the sides at a sufficient distance below the top to provide an intervening passage or channel to snugly receive the edges of the plate, and preferably are at the center of the sides, leaving the ends thereof 110 plain, extending along the center of the sides a sufficient distance to firmly lock the caps

- on the carlines. After the roof-panels are assembled upon their supporting bases between the carlines, the carline-caps are slipped into place on the carlines with their 5 ribs 27 under the carline plates 8, each being slid along the length of the associated carline beginning at its outer end from the eaves to the ridge-poles and its sides 25 enclose the flanges 23 of the adjacent panels; 10 when the cap is in position it is held against vertical displacement by its ribs, and its lateral flanges 26 hold the associated panels down on their bases, those parts thus being interlocked together to hold the panels and 15 caps in place and provide a weather-proof joint, but leaving sufficient clearance between the flanges and the carlines and caps to provide a flexible joint to permit the panels to move under strains or twisting actions 20 of the car and so prevent the buckling of their bodies or the fracture of their joints. The end-caps are then positioned over the outer ends of the carline-caps and the wings of the plates 8 to which they are bolted as 25 at 21, and are fastened to the car-body by the lag-screws 22, and the ridge-caps 13 are positioned over the inner ends of the carline-caps; the caps 13 also carry the saddles 28 for the running-boards 29.
- 30 The carline composed of the wooden body and metal top-plate is of advantage in making repairs and replacements of car-roofs, as the parts are easily and quickly assembled without disturbing surrounding elements, and the cost of an all-metal carline is 35 appreciably reduced without sacrificing any utility as a base for the adjacent sheets or panels and to which they can be interlocked by the caps.
- 40 I claim:
1. In a car-roof, a carline composed of a wooden body having a central ridge and a metal top-plate secured to the ridge and extending beyond its sides from the ridge to
- the eaves, roof-panels adjacent the carlines 45 and having upturned lateral flanges adjacent the ridges thereof and under the top-plate, and a cap on the plate covering the flanges of adjacent panels.
2. In a car-roof, a carline composed of a 50 wooden body having a central ridge and a metal top-plate secured to the ridge and extending beyond its sides from the ridge to the eaves, roof-panels adjacent the carlines and having upturned lateral flanges adjacent 55 the ridges thereof and under the top-plate, a cap on the plate embracing the flanges of the panels, the outer end of the plate providing a wing constructed to overlie the end of the ridge, and an end-cap 60 bolted to the wing.
3. In a car roof, a carline composed of a wooden body having a central ridge and a metal top-plate secured to the ridge and extending beyond its sides, roof-panels adjacent 65 the carlines and having upturned lateral flanges adjacent the ridges thereof, a cap on the carline having sides extending down upon the panels outside their flanges and provided with inwardly directed ribs to 70 engage the sides of the plate, the outer end of the plate forming a wing to overlie the outer end of the ridge, and an end-cap bolted to the wing.
4. In a car-roof, a carline composed of a 75 wooden body having a central ridge and a metal top-plate secured to the ridge and extending beyond its sides and outer end, the body being cut-away at its outer end, a flashing-strip under the carline-ridge, the outer 80 end of the top plates forming a wing to overlie the end of the ridge, roof-panels adjacent the carline having flanges, a carline-cap embracing the plate and covering the flanges, and an end-cap on the end of the 85 carline-cap and bolted to the wing.

In testimony whereof I affix my signature.
JOHN PEARSON.
